Canada

Application January 29, 1940, Serial No. 316,111

13 Claims. (Cl. 93—18)

This invention relates to a machine for making bags from thermo-plastic materials and particularly to a machine for making bags from a transparent material known under the trade name of "Pliofilm."

One of the objects of the present invention is that of providing a machine which will manufacture bags from a roll of material in a continuous manner wherein a tube of any desired cross section is first formed and portions are cut off and sealed at one end and wherein the bag shaping unit, sealing units and cutting unit incorporate novel features necessary for the proper handling of this material.

Another object of this invention is to provide a means of forming the material into a tube in a much shorter space than heretofore required, and at the same time to provide means of quickly altering the size and shape of the tube.

When more than one thickness of material such as Pliofilm is cut, there is a tendency toward permanent adhesion of the sheets at the adjacent edges and I have found that it is not practical to utilize the methods of cutting the bags by the means heretofore employed. Accordingly, I have incorporated certain novel features which will be described in detail, whereby the cutting is done without this objectionable adhesion.

Another object of the invention is to provide a mechanical movement for operating the bag sealing and cutting mechanism whereby a plurality of different lengths of bags may be formed with the same machine. In the following specification this part of the bag machine will be referred to as the multi-sizer.

As a number of bag users require printed matter on the finished bag, and as it is customary to print the sheet material prior to its being formed into a bag, it is necessary to have the cutting and sealing mechanism so timed that the bag-end sealing and cutting will be done at the correct intervals in order that the printed matter will appear in its proper position on the finished bag. However, in spacing the printing on an elastic material or in constructing any mechanical movement, it is not practical to obtain absolute accuracy. It is, therefore, still another object of this invention to provide the machine with a manual adjustment whereby the necessary correction of the timing of the end sealing and cutting means with the printed matter may be achieved from time to time, as may appear necessary, during any particular run.

Other and further features of the invention

will be pointed out in the following specification, which is a full, clear and exact description of the construction and operation of the machine constituting the present invention.

5 Figure 1 is a top plan view of the bag making machine constructed in accordance with this invention.

Figure 2 is a front elevation view.

Figure 3 is an end elevation of the right hand 10 end (Figures 1 and 2) which end carries the bag cutting means and the means for sealing the end of the bag.

Figure 4 is a fragmentary vertical sectional view taken on the line 4—4 of Figure 1 on a larger 15 scale to show details of the cutting mechanism.

Figure 5 is a sectional view of the bag shaper taken on the line 5—5 of Figure 1.

Figure 6 is an enlarged detail fragmentary view 20 of the bag shaping means and the means for sealing the lapped edges of the tube.

Figure 7 is a perspective view of the shaper.

Figure 8 is a cross-sectional view on the line 25 8—8, Figure 6.

Figure 9 is an enlarged detail fragmentary view 30 of the bag shaping means wherein provision is made for forming a gusset type bag.

Figure 10 is a cross-sectional view taken on the line 10—10 of Figure 9.

Figure 11 is a fragmentary side elevation showing 35 the means for adjusting the bag-end sealing means.

Figure 12 is a plan view of the mechanical movement for driving the various moving parts of the apparatus, said movement to be hereinafter 40 termed the multi-sizer.

Figure 13 is a side elevation of the multi-sizer.

Figure 14 is a plan view of a flat type bag.

Figure 15 is a cross-sectional view on line 15—45 15 of Figure 14 showing the seam where the lapped edges of the sheet are joined.

Figure 16 is a plan view of a gusset type bag.

Figure 17 is a cross-sectional view on the line 45 17—17 of Figure 16.

Figure 18 is an elevation of the side opposite to that shown in Figure 2.

Figure 19 is a fragmentary plan of the bag shaping means on an enlarged scale to show details not clearly visible in the other views.

50 Like characters of reference refer to like parts throughout the specification and drawings.

In the complete assembly illustrated in Figures 1, 2 and 3, the frame for supporting the various component parts of the bag making mechanism includes a pair of spaced bases 10, 11 con-

nected together by a pair of spaced-apart horizontal members 12, 13 which carry the multi-sizer hereinbefore mentioned and to be hereinafter more particularly described. The right hand base 11 (Figure 1) (hereinafter referred to as the front base) carries a superstructure 14 which supports the means for sealing one end of the bag and also the means for cutting the bag from the sheet material. The left hand base 10 (hereinafter referred to as the rear base) has mounted thereon a superstructure 15 which carries a number of rollers for the preliminary unwinding of the sheet material and the mechanism for performing the first step in forming the bag. Suspended between and carried by the superstructures 14, 15 are spaced cross members 16 which are located above and parallel to the members 12, 13, the cross members 16 serving as a support for the mechanism for shaping the bag and sealing the side edges of the sheet material at the completion of the shaping operation. Extending upwardly from the superstructure 15 are two spaced-apart posts 17.

The rear corner pieces 19, 20 project above the top of the base and are each provided with a bracket 21. Carried by each bracket is a pivoted arm 22, these arms forming a pair for supporting a shaft 23 upon which is mounted a roller 24. In order that arms 22 may be swung on their pivots, the purpose of which will be made more apparent in a subsequent part of the description, an adjustment is provided consisting of a quadrant-shaped rack 25 which is fixed to one of the arms 22 and actuated by a worm 26 manually rotatable by handle 27. Immediately below the pivot of the arms 22 and carried by brackets 21 is a roller 28. Carried by the base directly below the roller 28 is a roll 29 of sheet material 30 from which the bags are made and 40 of the kind described.

Except where specifically mentioned, all of the hereinbefore mentioned rollers and those herein-after mentioned lay in a horizontal plane and are parallel to each other.

The superstructure 15 carries a pair of rollers 31, 32, one directly above the other and in contact with each other. The lower roller 32 is driven by the power unit 33 in the manner herein-after described and for this purpose the shaft which carries the roller 32 is extended through the superstructure and is provided with a bevel gear 34 which meshes with and is driven by a bevel gear 35 mounted on the top of a vertical shaft 36 which is journaled in bearings 37, 38.

Carried by the superstructure 15 on the side opposite to the one which supports the roller 24, is a roller 39 which is substantially at the same elevation as the upper roller 31.

Suspended between and carried by the posts 17 are two rollers 40, 41, the roller 41 being at a higher elevation than the roller 40. The roller 40 is on the side of the posts which face towards the superstructure 14 and the roller 41 faces towards the rear.

The means for shaping the sheet material into a bag comprises a pair of vertical rollers 42, 43 which are carried on brackets 44, joined at the top by a cross bar 44a and at the bottom by a cross bar 44b, one bracket being mounted on one of the cross members 16 and the other being mounted on the other cross member 16, both brackets being positioned between the superstructures 14, 15, the vertical rollers being located centrally between the two cross members 16. In order that the 75

rollers 42, 43 may be correctly spaced with respect to each other, an adjustment is provided for the bearings 171 in which the rollers are journaled, as shown in Figure 19. Each bearing 5 which supports the upper and lower ends of each roller respectively is slidably carried on shaft 168 which is threaded to receive an adjusting nut 169. Each of the cross bars 44a, 44b are provided with a pair of spaced brackets 170, each bracket supporting one of said shafts 168. Between the upper pair of bearings 171 is a compression spring 172 which forces each bearing 10 against its respective adjusting nut 169. A similar compression spring (not shown) is provided for the lower pair of bearings.

The first step in shaping the material is performed by a triangular table 45 which acts in conjunction with the vertical rollers. The base 20 of the table is suspended between the posts 17 and supported by brackets 46 carried by the posts 17. The table is also provided with a central rib 25 for the purpose of reinforcement. In the present embodiment, it is necessary for the base of the table to be at a higher elevation than the apex 30 and for this purpose the base of the table is mounted at the same elevation as the roller 41 and approximately at the same elevation as the upper end of the rollers 42, 43. The table extends from the posts 17 to the rollers 42, 43, the apex of the table being located centrally between the rollers 42, 43 at approximately the lower end thereof.

The second step in the shaping operation is 35 performed by shaper 48 which is formed of two triangular-shaped plates 49, 50, which are held in spaced relationship to a triangular-shaped rib 50a, the apex of the plates being located centrally between the vertical rollers 42, 43. The rib 50a, which has its widest part adjacent the said rollers, passes between the rollers and is attached to a support 58. The ends of the plates 49, 50 adjacent the rollers 42, 43 are spaced apart in a vertical direction a distance equal to one-half the width of the sheet material. The 45 two plates converge together at the end indicated by numeral 59, the width of the end 59 in a horizontal direction being slightly less than one-half the width of the sheet material. The top plate 49 is provided with an overlying guide 51, the purpose of which will be clear in the description of the operation of the machine. Adjacent the end 59 is a pair of vertically adjustable members 52, 52a, one of said members being carried on bracket 53 which is secured to one of the cross members 16, midway between bracket 44 and superstructure 14 and the member 52a on bracket 53a similarly located on the other cross member 16. In order that the members 52, 52a 55 may be adjusted vertically, the bolt 54 which holds each member in place is passed through a slot 55 formed in each of the said members and one edge of each member is formed with a rack 56 which is engaged by a manually rotatable pinion 57 carried on the brackets 53, 53a, respectively.

Extending between members 52 is a shaft 60 which has one end projecting beyond one of the members 52 and has mounted thereon a pinion 61, a sprocket 61a, which drives pinion 61, and an arm 62 which is swingably mounted thereon between the pinion 61 and the member 52. The free end of the arm 62 carries a sleeve 63 into which is inserted a rotatable stub shaft 64 which has mounted thereon a wheel-shaped electrically

heated sealing unit 65, the sealing unit being aligned with the longitudinal axis of the shaper 48. The stub shaft 64 projects beyond the sleeve and has mounted thereon a pinion 66 which is of the same size as the pinion 61 and in mesh therewith. In Figure 2, the sealing unit is shown in its sealing position and in Figure 6, it is shown lifted out of the sealing position. The sealing unit is held in this last mentioned position by pawl 67 engaging in a recess formed in the upper part of member 52, the pawl being pivotally carried on lever 68a which is secured to arm 62. As the tube will tend to adhere to the sealing unit 65 after the lapped edges have been sealed together, a bifurcated foot 173 is carried on shaft 60 and is positioned so that the sealing unit, when in sealing position, will be between the arms of said foot and spaced slightly above plate 49 so the tube can pass between the said plate and foot. In order that the tube may be pressed firmly against the sealing unit during the sealing of the lapped edges, a spring 174 is secured to the underside of the plate 49, said spring projecting through an elongated slot 175 formed in the plate 49 immediately below the sealing unit 65. In front of the end 59 is a pair of rollers 68, 69 which are carried on arms 70, secured to the member 52. The roller 68 is not rotatable and has its top portion parallel to and in alignment with end 59 of the shaper. The roller 69 has its axis of rotation in alignment with the top periphery of the roller 68.

Housed in the upper part of the superstructure 14 is a pair of rollers 71, 72. The rear roller 71 is driven in the manner hereinafter described and also acts as the means for driving the sprocket wheel 61a. For this purpose, the shaft on which the roller 71 is mounted is provided with a sprocket wheel 74. The driving connection between sprockets 61a and 74 is established by means of a chain 75, an idler 76 keeping the correct tension on the chain. Roller 72 is driven by roller 71 through a pair of gears and is held in contact with it by springs.

The unit for sealing the ends of the bags is carried by the superstructure 14 immediately below the rollers 71, 72 and includes a pair of rollers 77, 78 which are journaled in a pair of spaced and vertically adjustable bearings 79, 80 (see Figure 11), which are adapted to slide vertically on guide rails 81, 82. The vertical adjustment of the bearings 79, 80 is effected by screws 83, 84 which support the bearings 79, 80 in their proper position, each screw being extended through and above the superstructure and having mounted on the projecting part, a gear wheel 85 which meshes with a gear 86 mounted on a shaft 87 carried on the top of the superstructure. The shaft 87 is adapted to be rotated manually and for this purpose is provided with a crank 88.

The front roller 78 carries an electrically heated sealing unit 89 which extends the full length of the roller. The shaft carrying the roller 78 has mounted thereon a bevel gear 90 and the shaft carrying the roller 77 has mounted thereon a bevel gear 91. A guide roller 92 is mounted over the rollers 77, 78 and carried by bearings 79, 80; and a guide roller 93 is mounted below the rollers 77, 78 and carried by the bearings 79, 80. The axes of rotation of the rollers 92, 93 are in alignment vertically and in alignment with the periphery of the roller 77 which faces the roller 78.

After passing the sealer 89, the sheet material

passes close to a pad 94 of moistened felt so that the electrostatic charge which the material has picked up in passing through the machine will be discharged.

Below the pad 94 is a driven roller 95 and an idler 96 (see Figure 4) which is carried on a pivoted arm 97 spring tensioned by spring 98 so as to press the idler firmly against roller 95. The roller 95 and idler 96 maintain the flattened tube under an even tension and cooperate with guide rollers 92, 93, to prevent the adhesion of the tube to the electrically heated sealing unit 89. A vertical drive shaft 99 is mounted on the right hand side of the superstructure 14 (Figure 3) and carries a bevel gear 100 meshing with a bevel gear 101 mounted on the shaft of the roller 71; a bevel gear 102 which meshes with the bevel gear 91; a bevel gear 103 which meshes with a bevel gear 104 carried on the shaft of the roller 95 and at its lower end a bevel gear 105.

Immediately below the roller 95 is the mechanism for cutting the formed bags from each other and includes a steel roller 106 (see Figure 4) which is mounted on anti-friction bearings and a rotating shaft 107 which carries knives 108. It has been previously explained that, owing to the natural adhesion of the material, it is not practical to use the means heretofore employed for cutting. It is, therefore, proposed to provide a facing for the roller 106 which will not injure the edge of the knives and which will have sufficient density to provide a suitable surface against which the bags can be cut without applying excessive pressure. A medium weight cardboard is a suitable material for this purpose and there is provided a roll 109 of sheet cardboard indicated by numeral 110 which passes over the roller 106 presenting one of its surfaces to the cutting edges of the knives 108, the cardboard being rewound, as used, on a rewind roll 111. The roll 111 is driven by a friction wheel 112, which is so adjusted as to maintain a constant tension on the roll 111 whereby the cardboard between the roller 106 and the rewind roll 111 will be kept taut. Intermediate between the rewind roll 111 and the roll 106, the cardboard passes over a roller 114. Above and slightly in front of the roller 114 is a rotating paddle 115, the edges of the paddle being timed to press the cardboard tightly against the roller 114 and cause the cardboard to be pulled over the roller 106 during the cutting operation and then continue the movement of the cardboard approximately $\frac{1}{8}$ " after the completion of each end-sealing and cutting operation. It is further pointed out that the paddle 115 rotates synchronously with the knives 108.

In order to reduce the amount of cardboard used at each cutting operation a means is provided to retract the cardboard a predetermined distance after each advance but such retraction is slightly less than the advance, thereby presenting at each cutting operation a new surface to the cutting edge of the knives. The means for retracting comprises a pair of members 116 which is pivotally carried by brackets 117a mounted on the side of the superstructure facing the shaper. The space between the member 116 is of such a width that it will straddle the cardboard and is provided, at the lower end, with a pair of spring tensioned gripping members 117, 118 between which the cardboard passes before travelling over the roller 106. The tension on the gripping members is such that the cardboard will not slide therebetween, thereby caus-

ing the member 116 to move when the paddle draws the cardboard over the rollers 106, 114 during the sealing and the cutting operations and this movement of the member 116 continues until further movement is arrested by contact with the superstructure. At this point, the cardboard slides between the members 117, 118 and continues to advance until the paddle 115 moves out of engagement. In the present construction, this further advance amounts to approximately $\frac{1}{16}$ " but this may be varied according to requirements.

As soon as the paddle 115 moves out of engagement, the member 116 returns to its normal position through the action of spring 119, which movement retracts the cardboard. It will be apparent that such retraction is less than the total advance. In order that the movement of member 116 may be varied, a set screw 120 is provided.

The driving mechanism for operating the several rollers, sealer, knives and other parts includes a multi-sizer, the unit as a whole being designated by numeral 121 and which is so constructed that the rollers 71, 95, 77, 31 and sealing unit 65 are rotated at a constant speed irrespective of the size of the bag and the puncher operated by roller 32, sealer 78, knives 108, paddle 115, are rotated at a speed which may, for some sizes of bags, be faster or slower than the speed at which the rollers 71, 95, 77, 31 and the sealing unit 65 may be rotating but, during the sealing of the bag-end and the cutting of the bags, will be uniform with the rotation of the rollers 71, 95, 77, 31 and sealing unit 65. The manner in which the mechanical movement is constructed for obtaining this will be described specifically with reference to Figures 12 and 13. For the purpose of describing the driving mechanism, it will be sufficient to describe the power output of the multi-sizer for driving the rollers 71, 95, 77, 31, sealing unit 65, sealer 78, puncher on 32, knives 108 and paddle 115.

The power unit 33 which in the present case is an electric motor includes a reducing gear-train housed in casing 122. A chain drive 123 establishes a driving connection between the power output 124 of the gear train and driven sprocket 125 of the multi-sizer, the sprocket 125 driving all the gears and operative parts of the multi-sizer. The multi-sizer has two power outputs, one for the group consisting of the rollers 71, 95, 77, 31 and sealing unit 65 which for convenience will be hereinafter referred to as group "A" and one for the roller 32, sealer 78, knives 108 and paddle 115 to be hereinafter referred to as group "B." The power output for group "A" comprises a sprocket wheel 126 and the power output for group "B" comprises a sprocket wheel 139.

The power transmission for group "A" consists of a drive shaft 127 which extends horizontally the full length of the bag making machine and which is carried in bearings 128 secured to the front and rear bases 11, 10, respectively. The shaft 127 has mounted thereon a sprocket wheel 128a which is driven by the sprocket wheel 126 through the medium of a chain drive 129. The driving connection between the shaft 127 and the vertical shaft 99 is accomplished by means of a bevel gear 130 mounted on the shaft 127 and having a driving connection with a bevel gear 131 which is mounted on the lower end of the shaft 99. The 75

driving connection is established between the roller 31 and the power output 126 by means of a vertical shaft 132 carried by the base 10, the upper end of the shaft 132 being provided with a bevel gear 133 which meshes with a bevel gear 134 carried on the end of the shaft which supports the roller 133, and the lower end of the shaft 132 being provided with a bevel gear 135 which meshes with a bevel gear 136 mounted on the shaft 127.

It is pointed out that the gears 91, 100, 101, 102, 103, 104, 130, 131, 136, 135, 133 and 134 have all the same tooth ratio so that the rollers which they drive will all rotate at the same rate of speed. As the portion of the shaft 127 which is carried by the rear base 10 lies outwardly from the balance of the shaft, there is provided a pair of gears mounted respectively on adjacent ends so that a driving connection is maintained between both portions of the shaft.

On the side opposite to the one which carries the shaft 127 is a shaft 140 which drives group "B." The shaft 140 is carried by bearings 141, 142 and extends from the base 10 to approximately the forward end of the base 11. A driving connection between the power output 139 and the shaft 140 is established by means of a sprocket wheel 143 which is mounted on the shaft 140 and drive chain 144. Mounted on the shaft 140 is a bevel gear 145 which meshes with and drives a bevel gear 146 mounted on the shaft which carries the paddle 115. The shaft which carries the paddle is also provided with a pulley wheel (not shown) adjacent to the bevel gear 146 for driving the belt 113. A driving connection with the shaft 140 for the sealer and the knives is established by means of a vertical shaft 147 mounted on the side of the superstructure 14, the shaft 147 carrying a bevel gear 148 which meshes with a bevel gear 149 carried on the shaft supporting the electrically heated sealing unit. The shaft 147 is also provided with a bevel gear 150 which meshes with a bevel gear 151 mounted on the shaft which carries the knives 108. The lower end of the shaft 147 is provided with a bevel gear 152 which meshes with and is driven by a bevel gear 153 mounted on the shaft 140. The upper bearing 154 for supporting the shaft 147 is carried on the vertically movable bearings 79 so that the upper bearing 154 will move vertically when the bearings 79, 80 are adjusted to various positions. The bevel gear 148 is mounted on the shaft 147 so that it will slide vertically on the shaft 147 with the bearing and thus be kept in mesh with the bevel gear 149 and permit the adjustment of the bearings 79, 80.

The roller 32 carries a device for punching a hole in the material which, when the bag is completely formed, will leave an indent 155 in the top edge of each bag, the form of the bag being shown in Figure 14. The roller 32 and the aforesaid cutting device, which is not shown in the drawings, rotates synchronous with the sealer and the knives. The driving connection between the shaft 140 and the vertical shaft 36 consists of a shaft 156 mounted horizontally on the base 10 parallel to and at the same elevation as the shaft 140, the shaft 156 being provided with a bevel gear 157 which meshes with and drives a bevel gear 158 mounted on the shaft 36, the shaft 156 being driven from the shaft 140 by means of a gear 159 mounted on the shaft 140 and which drives a gear 160 mounted on the shaft 156.

The construction and operation of the multi-

sizer, which is shown in Figures 12 and 13, will now be described.

The multi-sizer is provided with an input shaft 200 which has mounted on one end thereof the sprocket 125. At the other end of the input shaft is a train of change gears 201 which connect the shaft 200 to shaft 202. The shaft 202, by means of a chain 204 drives a shaft 203, the shaft 203 carrying a wheel 205 consisting of two rigidly connected plates having three equally spaced pins 211 near the outer edge thereof. A shaft 206 carries a standard Geneva motion wheel 207 which is actuated by the pin 211 carried on the wheel 205.

Carried on the shaft 200 is a lever 208 which is actuated by a cam 209. The lever 208 carries a pin 210 which at correctly timed intervals moves into one of the slots of the Geneva motion wheel 207 to lock the same in position when the latter is not turning, that is, during the interval between disengagement of one of the pins 211 from a slot in the Geneva motion wheel 207 and engagement of the next pin with another slot. The multi-sizer is provided with a shaft 212 which is driven by the shaft 206 through change gears 213, the shaft 212 having mounted on its inner end a gear 214. Coaxial with the shaft 212 is a shaft 215 which has a gear 216 mounted on the end adjacent the gear 214. The outer end of the shaft 215 is provided with a sprocket 139 and a hand wheel 218. The sprocket 139, which is the power output for group "B," drives the sprocket wheel 143 which is mounted on the shaft 140. The hand wheel 218 is provided as a matter of convenience when replacing the change gears 213. Two circular plates 219 are spaced apart and rigidly connected by three equally spaced pins 222. The plates enclose the gears 214, 216, one of the plates 219 being journaled on the shaft 212 and the other plate 219 being journaled on the shaft 215. A sprocket 220 is fixed to one of the plates 219 and driven from shaft 200 through chain 221. Carried on one of the pins 222 and free to revolve on the same are two gears 223 and 224 which are rigidly connected together, the gear 224 meshing with the gear 214 and the gear 223 meshing with the gear 216.

It will be seen that rotation of the shaft 200 causes a rotation of the sprocket 220 and the plates 219 tending to revolve gears 223, 224 about gears 214, 216. Gear 216 and the shaft 215 may remain at rest or revolve at any speed in either direction, depending on whether the gear 214 and the shaft 212 are revolving or at rest, but as long as the gear 214 and the shaft 212 are at rest, gear 216, shaft 215 and sprocket 139 will revolve at a constant speed.

It is also evident that when pin 210 is in one of these slots of the Geneva motion wheel 207, the gear 214 must be at rest and that sprocket 139 must, therefore, be revolving at a constant speed, driven from the shaft 200 through chain 221, sprocket 220, plate 219, gears 223, 224, 216 and shaft 215.

When one of the pins 211 engages with a slot in the Geneva motion wheel 207 and pin 210 is retracted, the wheel 207 is caused to revolve one quarter revolution by the action of the pin 211 and the gear 214 is caused to revolve an amount and in a direction determined by the change gears 213. Thus, change of speed of the output sprocket 139 takes place, which may either advance or retard its motion, relative to the shaft 200.

Since the shaft 200 revolves at a constant speed, the ratio of change gears 201 will determine the frequency of the speed changes described above, and as also described, the ratio of the change gears 213 will determine the amount of speed, or in effect, the amount which sprocket 139 is retarded or advanced.

The power output for group "A" comprises two separate shafts 226, 228, the shaft 226 being driven by shaft 200 through chain 229 at a constant rate of speed. The shafts 226, 228 are connected in the same manner as shafts 212, 215 and this connection comprises a gear 227 which is mounted on the inner end of the shaft 226 and a fixed gear 225 mounted on the inner end of the shaft 228 which is normally stationary. Two circular plates 230, 231 are spaced apart and rigidly connected by three equally spaced pins 232. The plates 230, 231 enclose the gears 225, 227, the plate 231 being journaled on the shaft 226 and the plate 230 being journaled on the shaft 228. Carried on one of the pins 232 and free to revolve thereon are two gears 233, 234 which are rigidly connected together, the gear 233 meshing with the gear 225 and the gear 234 meshing with the gear 227. It will thus be seen from the foregoing that the sprocket wheel 126, which drives the sprocket wheel 128 feeds the material through the machine at a constant speed and that by means of manual operation of the hand wheel 330 the gear 225 may be rotated to cause a momentary change of speed of sprocket 126 and, consequently, advances or retards the material being fed through group "A."

The device previously mentioned for advancing or retarding the material as it is fed through the machine in order to position the printing is not necessarily a part of the multi-sizer but has, for convenience, been incorporated therewith in this instance.

It is evident that if the circumferential spacing of the blades 108 (Figure 4) is say, 6", they must be retarded 4" to cut a 10" bag or advanced 2" to cut a 4" bag.

From all of the foregoing, it will be evident that while the punching, bottom sealing and cutting operations are taking place, the gear 214 is stationary and the speed of rotation of group "B" coincides with the speed of rotation of group "A" so that the punching, sealing and cutting devices will be moving at the same speed as the material while they are in contact with it. Therefore, after each punching, sealing and cutting operation takes place, the gear 214 is caused to rotate a given amount, and group "B" is therefore advanced or retarded as the case may be so that the several units will come in contact with the material again at the correct intervals. Thus, the pin 211 actuates the wheel 207 and the gear 214 is caused to move once for each bag, and it is evident that with a constant speed of travel of the material, this must occur more frequently for short bags than for longer bags.

The bags are formed by the machine in the following manner. Starting at the roll 28 it will be seen that the transparent material 30 passes over the roller 28; then between the rollers 31, 32 and, as previously described, the cut-out 155 is formed while the material is passing between the rollers 31, 32. After passing between the rollers 31, 32, the material passes around the roller 39 back to the roller 24 and then to the rollers 40 and 41. After passing the roller 41, the transparent material travels underneath the triangular-shaped table 45, the material travelling in

the direction indicated by the arrows in Figure 2. The material 30 has a sliding contact with the underside of the table and its surface lies in a horizontal plane. At a point between the vertical rollers 42, 43 and due to the shape and position of the table 45 and the action of the vertical rollers 42, 43, the sheet material is folded in half and lies in a vertical plane with the two outside edges uppermost. After passing between the rollers 42, 43 the material is drawn over the shaper 48 with one edge of the material overlapping the other edge, the two edges being in contact with the top 49 of the shaper, which is so shaped as to gradually fold the material so that it will lie in a horizontal plane with the two overlapped edges positioned centrally of the material and of the shaper. By the time the material has reached the sealing unit 65, the change from a vertical to a horizontal position has been completed and the material folded into a flat tube, the two sides of which are separated by the shaper. Prior to leaving the shaper 48, the sealing unit 65 seals the two overlapping edges together, the spring 174 holding the tube against the sealing unit in the manner hereinbefore described, and the material leaves the shaper as a flattened tube. It is pointed out that by this means a tube of any desired cross-section is formed from a flat sheet in a very short distance but at the same time perfectly even tension is maintained in all parts of the material. This is important in the case of elastic materials. After leaving the shaper the folded material 30 passes over the non-rotatable roller 68 and underneath the roller 69. Due to the position of these two rollers and the fact that the roller 68 is non-rotatable, wrinkling of the material is at this point avoided. The material then travels over the roller 71 and passes downwardly between the rollers 71, 72 and then between the roller 71 and the sealing unit 69, the material being pressed against the roller 71 by the guide rollers 82, 83. The sealing unit is timed to form at properly spaced intervals a transverse seal across the material, each seal being double, with a small space between so as to form the sealed end of two bags simultaneously. After passing the sealer, the bags will be lying end to end and top to top but each bag will be united to adjacent bags. The knives separate the bags by cutting centrally through the double end seal, and midway between the end seals, that is, the end seals are two bag lengths apart but the knife cuts every bag length; thus, there is one bottom seal for every two cuts. The bags discharge onto slide 161 and are caught by roller 162 which throws them onto conveyor 163.

Since the apparatus which has been described is constructed for manufacturing different sizes of bags, it is necessary to describe the manner in which the apparatus is adjusted. As the puncher carried by the roller 32, the sealer 78, the paddle 115 and the knives 108 are synchronized, and as they perform their functions simultaneously, it is necessary to have the amount of material between the puncher and the knives divisible exactly into a definite number of bags. This is obtained by adjusting the arm 22 through the medium of the crank 30 to a position which will give the required amount of material between these two points. It is also apparent that it will be necessary to have the material between the sealer 78 and the knives divisible exactly into a definite number of bags. The sealer is spaced correctly with respect to the knives by raising 75

or lowering the sealer by means of the crank 30. The timing of the parts designated as group "B" is varied for different bag lengths by adjustment of the multi-sizer as previously explained.

5 The size of the cross section of the bag is varied by a change of the width of material and by substitution of other shapers 48 and plates 49-50.

The means by which a gusset type of bag is formed is shown in Figure 9 which is an elevation view of the shaper. Located between the plates 49, 50 of the shaper are two thin, triangular plates 164, 165, which are closer together at the end adjacent the end 59 of the shaper than they are at their other ends. The plate 165 is removably attached to member 52 by means of the arm 166 and the plate 164 is removably attached to the member 52 by means of the arm 167. The material, when passing over the shaper, will then have a fold formed in each side when it is desired to produce a gusset type of bag.

What I claim as new and desire to protect by Letters Patent of the United States is:

1. In a bag making machine for the manufacture of bags from a roll of sheet material, a plurality of rollers for feeding said material through the said machine at a constant rate of speed, said rollers being driven at a constant rate of speed, means for folding said material to form 25 a continuous tube with the edges of the material lapped, means for sealing the lapped edges of the tube together, rotating means for sealing the tube transversely at predetermined intervals to form the bottoms of the bags, rotating means for cutting 30 said tube into bags of a predetermined length, comprising a pair of cutting knives mounted diametrically opposite each other on a shaft rotated synchronously with said last mentioned sealing means, a rotatable roller, sheet material passing over said roller and presenting to said knives a surface against which said tube is cut, said material being of a density which will prevent the adhesion of the two adjacent edges formed by the knife, and means for moving 35 said material at the same rate of speed as the tube during the cutting operation.

2. In a bag making machine for the manufacture of bags from a roll of material, a plurality of rollers for feeding said material through the said machine at a constant rate of speed, said rollers being driven at a constant rate of speed and maintaining said material under a uniform tension, means for folding said material to form 40 a continuous tube with the edges of the material lapped, means for sealing the lapped edges of the tube together, rotating means for sealing the tube transversely at predetermined intervals to simultaneously form the bottoms of two bags, rotating means for cutting said tube into bags of a predetermined length, comprising a pair of cutting knives mounted diametrically opposite each other on a shaft rotated synchronously with said last mentioned sealing means, a rotatable roller, sheet material passing over said roller and presenting to said knives a surface against which said tube is cut, said material being of a density which will prevent the adhesion of the two adjacent edges formed by the knife, and means for moving 45 said material at the same rate of speed as the tube during the cutting operation.

3. In a bag making machine for the manufacture of bags from a roll of sheet material, a plurality of rollers for feeding said material through the said machine at a constant rate of speed, said rollers being driven at a constant rate

of speed, means for folding said material to form a continuous tube with the edges of the material lapped, means for sealing the lapped edges of the tube together, rotating means for sealing the tube transversely at predetermined intervals to form the bottoms of the bags, rotating means for cutting said tube into bags of a predetermined length, comprising a pair of cutting knives mounted diametrically opposite each other on a shaft rotated synchronously with said last mentioned sealing means, a rotatable roller, sheet material passing over said roller and presenting to said knives a surface against which said tube is cut, said material being of a density which will prevent the adhesion of the two adjacent edges formed by the knife, means for moving said material at the same rate of speed as the tube during the cutting operation and means retracting said material a distance less than the amount of advance whereby a new surface is presented to the knives for each cutting operation.

4. In a bag making machine for the manufacture of bags from a roll of material, a plurality of rollers for feeding said material through the said machine at a constant rate of speed, said rollers being driven at a constant rate of speed and maintaining said material under a uniform tension, means for folding said material to form a continuous tube with the edges of the material lapped, means for sealing the lapped edges of the tube together, rotating means for sealing the tube transversely at predetermined intervals to simultaneously form the bottoms of two bags, rotating means for cutting said tube into bags of a predetermined length, comprising a pair of cutting knives mounted diametrically opposite each other on a shaft rotated synchronously with said last mentioned sealing means, a rotatable roller, sheet material passing over said roller and presenting to said knives a surface against which said tube is cut, said material being of a density which will prevent the adhesion of the two adjacent edges formed by the knife, means for moving said material at the same rate of speed as the tube during the cutting operation, and means for rotating said last mentioned sealing means and said knives synchronously with said rollers during the formation of the transverse seal and the cutting of said tube and at a different rate of speed between said sealing and said cutting.

5. In a bag making machine for the manufacture of bags from a roll of sheet material, a plurality of rollers for feeding said material through the said machine at a constant rate of speed, said rollers being driven at a constant rate of speed, means for folding said material to form a continuous tube with the edges of the material lapped, means for sealing the lapped edges of the tube together, rotating means for sealing the tube transversely at predetermined intervals to form the bottoms of the bags, rotating means for cutting said tube into bags of a predetermined length, comprising a pair of cutting knives mounted diametrically opposite each other on a shaft rotated synchronously with said last mentioned sealing means, a rotatable roller, sheet material passing over said roller and presenting to said knives a surface against which said tube is cut, said material being of a density which will prevent the adhesion of the two adjacent edges formed by the knife, means for moving said material at the same rate of speed as the tube during the cutting operation, means for rotating said last mentioned sealing means and said knives synchronously with said rollers during the formation of the transverse seal and the cutting of said tube and at a different rate of speed between said sealing and said cutting.

6. In a bag making machine for the manufacture of bags from a roll of material, a plurality of rollers for feeding said material through the said machine at a constant rate of speed, said rollers being driven at a constant rate of speed and maintaining said material under a uniform tension, means for folding said material to form a continuous tube with the edges of the material lapped, means for sealing the lapped edges of the tube together, rotating means for sealing the tube transversely at predetermined intervals to simultaneously form the bottoms of two bags, rotating means for cutting said tube into bags of a predetermined length, comprising a pair of cutting knives mounted diametrically opposite each other on a shaft rotated synchronously with said last mentioned sealing means, a rotatable roller, sheet material passing over said roller and presenting to said knives a surface against which said tube is cut, said material being of a density which will prevent the adhesion of the two adjacent edges formed by the knife, means for moving said material at the same rate of speed as the tube during the cutting operation, and means for rotating said last mentioned sealing means and said knives synchronously with said rollers during the formation of the transverse seal and the cutting of said tube and at a different rate of speed between said sealing and said cutting.

7. In a bag making machine for the manufacture of bags from a roll of sheet material, a plurality of rollers for feeding said material through the said machine at a constant rate of speed, said rollers being driven at a constant rate of speed, means for folding said material to form a continuous tube with the edges of the material lapped, means for sealing the lapped edges of the tube together, rotating means for sealing the tube transversely at predetermined intervals to form the bottoms of the bags, rotating means for cutting said tube into bags of a predetermined length, comprising a pair of cutting knives mounted diametrically opposite each other on a shaft rotated synchronously with said last mentioned sealing means, a rotatable roller, sheet material passing over said roller and presenting to said knives a surface against which said tube is cut, said material being of a density which will prevent the adhesion of the two adjacent edges formed by the knife, means for moving said material at the same rate of speed as the tube during the cutting operation, means for retracting said material a distance less than the amount of advance whereby a new surface is presented to the knives for each cutting operation, and means for rotating said last mentioned sealing means and said knives synchronously with said rollers during the formation of the transverse seal and the cutting of said tube and at a different rate of speed between said sealing and said cutting.

8. In a bag making machine for the manufacture of bags from a roll of material, a plurality of rollers for feeding said material through the said machine at a constant rate of speed, said rollers being driven at a constant rate of speed and maintaining said material under a uniform tension, means for folding said material to form a continuous tube with the edges of the material lapped, means for sealing the lapped edges of the tube together, rotating means for sealing the tube transversely at predetermined intervals to simultaneously form the bottoms of two bags, rotating means for cutting said tube into bags of a

predetermined length, comprising a pair of cutting knives mounted diametrically opposite each other on a shaft rotated synchronously with said last mentioned sealing means, a rotatable roller, sheet material passing over said roller and presenting to said knives a surface against which said tube is cut, said material being of a density which will prevent the adhesion of the two adjacent edges formed by the knife, means for moving said material at the same rate of speed as the tube during the cutting operation, means retracting said material a distance less than the amount of advance whereby a new surface is presented to the knives for each cutting operation, and means for rotating said last mentioned sealing means and said knives synchronously with said rollers during the formation of the transverse seal and the cutting of said tube and at a different rate of speed between said sealing and said cutting.

9. In a machine for the manufacture of bags from material in the form of a continuous flat strip of thermoplastic material comprising means for continuously feeding said material and means for maintaining a relatively constant tension thereon, means for converting said flat strip into a closed tube including a triangular table-like member having its apex approximate to and slightly below two vertically mounted rolls, a shaping member on the opposite side of said vertical rolls and having a tapered end extending therethrough approximate to the apex of said table-like member, means for overlapping the edges of said strip over said shaping member thereby forming said strip into a tube and a heatable sealing element in alignment with the overlapped edges of said tube, and means for cutting said tube into pieces of predetermined length and means for sealing one end of each of said pieces.

10. In a machine for the manufacture of bags from material in the form of a continuous flat strip of thermoplastic material comprising means for continuously feeding said material and means for maintaining a relatively constant tension thereon, means for converting said flat strip into a closed tube including a triangular table-like member having its apex approximate to and slightly below two vertically mounted rolls, a shaping member on the opposite side of said vertical rolls and having a tapered end extending therethrough approximate to the apex of said table-like member, means for overlapping the edges of said strip over said shaping member thereby forming said strip into a tube and a heatable sealing element in alignment with the overlapped edges of said tube, rotatable cutting means for cutting said tube into pieces of predetermined length and transverse rotatable sealing means for sealing one end of each piece and means for rotating said rotatable cutting and sealing means at the same rate of speed during the cutting and sealing operations and at different rates of speed between the cutting and sealing operations.

11. In a machine for the manufacture of bags from material in the form of a continuous flat strip of thermoplastic material comprising means for continuously feeding said material and means for maintaining a relatively constant tension thereon, means for converting said flat strip into a closed tube including a triangular table-like member having its apex approximate to and slightly below two vertically mounted rolls, a shaping member on the opposite side of said

vertical rolls and having a tapered end extending therethrough approximate to the apex of said table-like member, means for overlapping the edges of said strip over said shaping member thereby forming said strip into a tube and a heatable sealing element in alignment with the overlapped edges of said tube, rotatable cutting means for cutting said tube into pieces of predetermined length and transverse rotatable sealing means for sealing one end of each piece and means for rotating said rotatable cutting and sealing means at the same rate of speed during the cutting and sealing operations, and including roller elements preventing the adhesion of the open ends of said bags.

12. In a machine for the manufacture of bags from material in the form of a continuous flat strip of thermoplastic material comprising means for continuously feeding said material and means for maintaining a relatively constant tension thereon, means for converting said flat strip into a closed tube including a triangular table-like member having its apex approximate to and slightly below two vertically mounted rolls, a shaping member on the opposite side of said vertical rolls and having a tapered end extending therethrough approximate to the apex of said table-like member, means for overlapping the edges of said strip over said shaping member thereby forming said strip into a tube and a heatable sealing element in alignment with the overlapped edges of said tube, means for sealing said tube at predetermined positions including a transversely disposed roller having adjacent heatable edges projecting therefrom at right angles to the movement of the tube and means for cutting said tube in predetermined lengths including a roller having at least one knife edge projecting at right angles to the movement of the tube and means for synchronizing the rotation of the cutting means with the rotation of the transverse sealing means.

13. In a machine for the manufacture of bags from material in the form of a continuous flat strip of thermoplastic material comprising means for continuously feeding said material and means for maintaining a relatively constant tension thereon, means for converting said flat strip into a closed tube including a triangular table-like member having its apex approximate to and slightly below two vertically mounted rolls, a shaping member on the opposite side of said vertical rolls and having a tapered end extending therethrough approximate to the apex of said table-like member, means for overlapping the edges of said strip over said shaping member thereby forming said strip into a tube and a heatable sealing element in alignment with the overlapped edges of said tube, means for sealing said tube at predetermined positions including a transversely disposed roller having two adjacent heatable edges projecting therefrom at right angles to the movement of the tube and means for cutting said tube in predetermined lengths including a roller having at least one knife edge projecting at right angles to the movement of the tube and means for correlating the movement of the tube and rotation of the transverse sealing and cutting means whereby the tube is cut between each of the adjacent sealed portions and substantially equidistant from each spaced apart sealed portion.

HARVEY M. RUTTER.
